UNITED STATES PATENT OFFICE

BENJAMIN BLACKMORE, OF CUYAHOGA FALLS, OHIO

RADIATOR

Application filed June 7, 1929. Serial No. 369,150.

This invention relates to new and novel improvements in radiators and while intended for use generally wherever it may be advantageously applied, it is particularly adapted for use in heating radiators in which connection it will be illustrated in the drawings and herein described.

Objects of the invention are to provide a strong, durable radiator of simple, construction which may be manufactured at a low cost and which will be very efficient in use.

A particular object is to provide a radiator composed of laminæ of relatively thin sheet metal held in flat abutting relation to form a laminated radiator of great strength and durability.

Further objects are to provide a laminated radiator built up of a plurality of sheets of metal and which may be quickly and conveniently formed by stamping and to provide a construction which will require a minimum of different stampings which in consequence may be provided with a low cost, of die and tool equipment.

The above objects are accomplished and additional ends are attained by the novel construction, combination and arrangement of parts hereinafter described and illustrated in the accompanying drawings in which I have shown one form of the invention, it being understood that the invention is capable of various adaptations and that changes and modifications may be made or resort had to substitutions and equivalents which come within the scope of the claims hereunto appended.

In the drawings like numerals of reference are employed to designate like parts as the same may appear in any of the several views and in which:—

Figure 1 is an end view of a radiator constructed in accordance with this invention,

Figure 2 is a side view of same.

Figure 3 is a plan view of one of the plates employed in carrying out the invention,

Figure 4 is a like view of a similar plate used in reducing the invention to practice,

Figure 5 is a top plan view having parts broken away and showing a portion of a radiator constructed in accordance with this invention,

Figure 6 is a plan view of one of the radiator fins employed in carrying out the invention,

Figure 7 is a horizontal sectional view of a portion of a radiator constructed in accordance with this invention,

Figure 8 is a fragmentary view showing in horizontal cross section, a modified form of the invention.

Proceeding now to a detailed description of the invention with reference to the particular adaptation thereof disclosed in the drawings, the main body of the radiator is composed of laminæ of sheet metal. The laminæ comprises two similar plates 10 and 11. Each of the plates 10 and 11 are formed preferably by stamping and differ only in that the plate 11 is somewhat longer and has a larger marginal edge than the plate 10.

The plates 10 and 11 are formed preferably by stamping, each being provided with a relatively large opening 12 which conforms in shape and size to the desired cross sectional shape and size of the cavity of the radiator. Each of the plates 10 and 11 is also provided adjacent the upper edge thereof with an opening 13 which is formed therein in spaced relation to the outer edge thereof. Each of the plates 10 and 11 is stamped to provide a raised bead 14, on one side thereof which extends therearound in spaced relation to the outer edge thereof and forms a corresponding groove 15 on the other side thereof.

The contour and extent of the beads 14 and the grooves 15 are identical in both the plates 10 and 11 whereby the bead 14 will nest in the groove 15 on the adjacent plate when the parts are positioned in abutting relation. The flat marginal edge 16 on the plate 11 is substantially wider than the marginal edge 17 on the plate 10. A plurality of plates 10 are positioned in flat abutting relation with one of the plates 11. A plate 10 is then added and another plate 11 is po-

sitioned in flat abutting relation thereagainst, thereby forming a groove or seat 18 adapted to receive the inner edge portion of one of the radiating fins 19. Other plates 10 and 11 are added in the same relation to form a radiator body of the desired length.

While the plates 10 and 11 may be of any desired contour to provide a radiator body of any desired shape, they are preferably formed with side edges which converge toward the upper edges thereof.

Each radiating fin 19 is provided with an opening 20 which extends from the lower edge thereof. The opening 20 conforms in shape to the size and contour of the plates 10 whereby each of the fins 19 will be snugly received on a plate 10 and be positioned between the plates 11.

When the plates 10 and 11 have been thus placed in flat abutting relation to form a radiator body of the desired length, a side member 21 is positioned on one side thereof and a side member 22 on the other side thereof. The side member 21 is provided with a rib 23 which is adapted to fit in the groove 15 in the plate 10 and the side member 22 is likewise provided with a groove which is adapted to receive the bead 14. The plates 10 and 11 with the side members 21 and 22 are then placed in a press and are forced in close abutting relation. A bolt 24 is then positioned through suitable openings in the side members 21 and 22 and through the aligned openings 13 in the plates 10 and 11 and the nuts 25 are threaded on the said bolt to hold the plates in flat abutting relation. The side plates 21 and 22 are likewise provided at a point immediately below the lower edge of the plates 10 and 11 with aligned openings in which a bolt 26 is positioned and secured by means of the nuts 27, thus securely holding the plates 10 and 11 and the side members 21 and 22 in assembled relation.

The side members 21 and 22 are preferably provided at the lower end thereof with flange extensions 28 which form legs adapted to support the radiator on a floor or other structure. The side plate 21 is provided with an inlet nipple 29 which is positioned thereon to provide the inlet opening 30 at the lower edge of the cavity of the radiator. The side member 22 is likewise provided with an outlet nipple 31. A pipe 32 leading from a source of steam, hot water or other heating fluid is attached to the nipple 29 and an outlet pipe 33 is operatively attached to a nipple 31. Suitable valves 34 and 35 may be positioned in the lines 32 and 33 to regulate and control the operation of the radiator.

In the modification of the invention shown in Figure 8, I have shown a plurality of plates 10 positioned in flat abutting relation with radiating vanes 36 interposed at regu-

lar intervals therebetween. The portion of each radiating vane 36 which abuts against the plate 10 is exactly like the plate 11, but extends outwardly to an extent which corresponds to the detachable fin 19 thereby forming a laminated structure in which the radiating fins 36 form a permanent part of the structure.

The plates 10 and 11 may be of any desired shape and size and may be provided with openings 12 which will form any suitable shape cavity.

While I have shown particular means for holding the laminae in abutting relation, it is understood that any suitable means may be employed.

Having thus illustrated my invention and described the same in detail, what I claim as new and desire to secure by Letters Patent is:

1. A radiator comprising thin metal laminae secured in flat abutting relation, each lamina having a relatively large like opening therein, said openings coinciding to form a radiator cavity and end members closing each end of said cavity.

2. In a radiator, metal laminae, each lamina having an opening of the same size and shape and means to secure said laminae in flat abutting relation with said openings coinciding to form a radiator cavity.

3. In a radiator, a body composed entirely of thin metal laminae certain of said laminae being of greater area than others, each lamina having an opening of the same size and shape and means to secure said laminae in flat abutting relation with said openings coinciding to form a radiator cavity.

4. In a radiator, metal laminae, certain of said laminae having a greater area than others, said laminae provided with communicating openings forming a radiator cavity, members for closing the ends of said cavity and means for securing said members and laminae in assembled relation said openings being of the same size and shape and located with their edges coinciding to form a relatively smooth cavity wall.

5. In a radiator, a radiator body composed of thin metal laminae of the same thickness, certain of said laminae having a greater area than others, said laminae provided with communicating openings of like size and shape forming a radiator cavity, means for closing the ends of said cavity and means to hold said members and laminae in assembled relation, the laminae of greater area being interspersed in said body in regularly recurring order.

6. In a radiator, a radiator body composed of metal laminae, certain of said laminae having a greater area than others, said laminae provided with communicating openings forming a radiator cavity, means for closing the ends of said cavity and means to hold

said members and laminæ in assembled relation, the laminæ of greater area being regularly interspaced in said body in pairs with a lamina of smaller area therebetween to 5 form a groove and a radiator fin detachably mounted in said groove.

7. In a radiator, a radiator body composed of metal laminæ, certain of said laminæ having a greater area than others, said laminæ 10 provided with communicating openings forming a radiator cavity, means for closing the ends of said cavity and means to hold said members and laminæ in assembled relation, the laminæ of greater area being regularly interspaced in said body in pairs with a lamina of smaller area therebetween to 15 form a groove and a radiator fin having an opening conforming in size and shape to the outline of a lamina of smaller area, said 20 fin fitted in said groove.

In testimony whereof I have hereunto set my hand.

BENJAMIN BLACKMORE.
